GEORGE J. MEUER AND WILLIAM C. STEVENS, OF MILWAUKEE, WISCONSIN, ASSIGNEES, BY MESNE ASSIGNMENTS, TO CUTLER-HAMMER, INC., OF MILWAUKEE, WISCONSIN, A CORPORATION OF DELAWARE

VACUUM-TUBE SOCKET

Application filed September 13, 1924. Serial No. 737,516.

This invention relates to vacuum tube sockets.

An object of the invention is to provide a socket of the above character of extremely simple and durable construction.

A further object is to provide a socket having contact clips of improved form.

A further object is to provide a socket having separately molded shell and base portions with novel means for detachably holding the same in assembled relation.

A further object is to provide a socket enabling insertion or removal of a tube by a straight telescopic movement.

A further object is to provide a relatively large positive contact area of the tube prongs or electrodes and the contact clips.

A still further object is to improve and simplify the construction of such sockets in general, including wide spacing of the current carrying parts both in air and insulation.

Other objects and advantages will be apparent to those skilled in the art in the course of the following description, reference being had to the accompanying drawing, in which:

Figure 1 is a perspective view of the socket; with the parts in assembled relation;

Fig. 2 is a similar view with a portion of the shell broken away for purposes of illustration;

Fig. 3 is a top plan view of the socket;

Fig. 4 is a vertical section on the line 4—4 of Fig. 3;

Fig. 5 is a vertical section on the broken line 5—5 of Fig. 3, and

Fig. 6 is an enlarged perspective view of one of the contact clips.

Referring to the drawing, in which like parts are designated by like characters of reference in the several figures, the socket comprises a base 10 of insulating material, preferably of the type comprising a filler and an organic binder and sold commercially under the name of "Thermoplax"; said base having a recess 11 therein adapted to receive a relatively thin cylinder or shell 12 of insulating material, such as the phenol-

formaldehyde condensation product sold commercially under the name of "Bakelite." Base 10 is provided with a projection 13 adapted to cooperate with a notch 14 in the shell 12 for insuring proper angular positioning of a given point in the circumference of the latter with respect to the base, as hereinafter more fully described.

Shell 12 is provided near the bottom thereof with a plurality of spaced openings 15, said openings being preferably in alignment with the respective corners of the base. Contact clips 16 are adapted to project through the respective openings, and are provided at opposite ends thereof with pairs of upturned lugs or ears 17 and 18. Lugs 17 are adapted to be definitely positioned within shell 12 for cooperation with the prongs or electrode terminals of a vacuum tube (not shown). Thus, base 10 is provided with channels or grooves 19 for insuring positive radial alinement of the clips 16 with respect to shell 12, and said clips are secured to the base by screws 20. Said screws are located in countersunk portions 21 of the base (Fig. 4), and project through holes 22 into engagement with the indent screw threaded portions 23 of clips 16 for securing the latter to the base. Holes 22 are enlarged at the upper ends thereof as indicated at 24 to accommodate the portions 23 of the clips. Lock washers 25 are preferably provided on screws 20 for more rigidly securing clips 16 in position.

As clearly shown at 26 in Fig. 5, the clips 16 are adapted to engage or bite into the walls of openings 15 in shell 12 upon tightening of the screws 20, thus serving to rigidly clamp the base and shell against relative longitudinal movement.

Referring more particularly to the contact clip as shown in Fig. 6 and the other figures, the lugs or ears 17 at the inner end of the clip are slightly convex with respect to each other, the upper ends of said lugs being flared outwardly to insure proper reception of the prong or electrode terminal of a vacuum tube therebetween, said lugs being sufficiently resilient to compensate for possible inaccuracies in manufacture of 100

the tube or the socket. The lugs 17 thus provide a clip contact with the prongs of the tube, thereby insuring wiping engagement with both sides of the prongs to clean the same when the tube is inserted in the 5 socket. The metal parts of the socket are preferably silver plated to insure perfect contact surfaces, thus also tending to improve the appearance of the completed article.

10 The lugs 18 at the outer end of each of the clips 16 are substantially parallel to each other to provide for positioning of a circuit wire to be soldered or otherwise suitably secured thereto. The clips 16 are of reduced width adjacent the lugs 18 to permit ready bending of the latter downwardly over the base 10 for underwiring, as indicated in dotted lines at 27 in Fig. 2. By 15 the provision of integral or one-piece metallic elements to bridge the vacuum tube electrodes and the circuit wires, perfect electrical conductivity therebetween is insured inasmuch as the usual binding posts and joints are eliminated,—it being noted 20 that the screws 20 are not a part of the electric circuit. However, it is obvious that if necessary or desirable the nuts 28 may serve to bind the circuit wires to the respective clips 16. Said nuts are primarily intended, however, to lock the screws 20 against rotation, and are preferably provided with polygonal sides and also with 25 slots 29 in the tops thereof, to permit 30 tightening by either a wrench or a screw driver.

The shell 12 is provided at the upper end thereof with a vertical notch 30 for cooperation with the usual pin or projection 40 on a vacuum tube to insure engagement of the prongs of the latter with the proper contacts of the base. The usual indicia may be provided on the base for insuring proper circuit connections.

45 In assembling the device, tube 12 is inserted into recess 11 of base 10, the engaging portions 13 and 14 insuring proper location of the notch 30 with respect to the several contact clips 16 which are inserted 50 through openings 15 and then clamped to base 10 by means of screws 20, said clips 16 serving, as aforesaid, to securely clamp the shell and base together. By our improved construction the pairs of lugs or 55 ears 17 are relatively widely spaced within shell 12, thus insuring proper current carrying characteristics of the conducting elements of the device.

60 In use, a vacuum tube is inserted into shell 12 with the pin on said tube in alignment with notch 30, only a straight or vertical movement of the tube being necessary to effect contacting and holding of the 65 prongs of said tube by the resilient clip

contacts 17; whereas the tube may be removed from the socket by a like vertical movement in the opposite direction.

By providing a socket in which the base and shell may be separately molded, the 70 same may be individually formed of different grades of insulating material, while also permitting various attractive color combinations of the insulating materials employed. 75

While we have shown but one form of device embodying our invention, it will be apparent to those skilled in the art that various modifications may be made therein without departing from the spirit and 80 scope of the invention as defined by the appended claims.

What we claim as new and desire to secure by Letters Patent is:

1. A vacuum tube socket comprising a 85 molded insulating base having a recess in the top surface thereof to provide a shoulder, a separately molded insulating shell adapted to rest on said shoulder, cooperative engaging portions on said shell and base to properly position the same and prevent relative rotary movement thereof, said shell having a plurality of circumferentially spaced 90 openings therein adjacent to said base, and a plurality of combined contact terminal 95 and clip members secured to said base and extending inwardly through the openings in said shell, said members being adapted to positively engage the walls of said openings to thereby hold said base and shell 100 against relative longitudinal movement.

2. A vacuum tube socket comprising a 105 molded insulating base having a circular recess in the top surface thereof providing a shoulder, a separately molded cylindrical insulating shell adapted to rest on said shoulder, said shell having a longitudinal slot in each of its upper and lower edges, a projection on said base cooperating with the shoulders formed by the lower slot to insure proper positioning of said shell and to prevent relative rotary movement thereof with respect to the base, a plurality of combined contact and terminal members secured to the upper surface of said base and extending through said shell at spaced points in the circumference of the latter, said combined contact and terminal members having intermediate portions adapted to engage the walls of said shell to thereby clamp the 115 latter to the base.

3. A vacuum tube socket comprising a 120 molded insulating base having a circular recess in the top surface thereof providing a shoulder, a separately molded cylindrical 125 insulating shell adapted to rest on said shoulder, said shell having a longitudinal slot in each of its upper and lower edges, a projection on said base cooperating with the shoulders formed by the lower slot to 130

insure proper positioning of said shell and to prevent relative rotary movement thereof with respect to the base, a plurality of combined contact terminals and clips removably and adjustably secured to the upper surface 5 of said base and extending through said shell at spaced points in the circumference of the latter, said combined contact terminals and clips having intermediate portions adapted to engage the walls of said shell to thereby clamp the latter to the base.

4. A vacuum tube socket comprising a molded insulating base having a substantially central opening, said base being additionally recessed from its upper surface 15 to provide a substantially annular shoulder, a separately formed tubular insulating shell adapted to rest on said shoulder, means integral with the shell and base respectively 20 to insure a given relative rotary positioning thereof, said shell having a plurality of circumferentially spaced openings adjacent to the lower end thereof, a plurality of combined contact terminals and clips freely insertable through said openings in the shell 25 and adapted to rest upon the upper surface of said base, means for adjustably clamping said combined contact terminals and clips to said base, and means on the former to positively engage the walls of said openings 30 to thereby clamp said shell to said base.

5. A combined contact clip and terminal for vacuum tube sockets, comprising a single metal blank having a relatively long 35 body portion and longitudinally aligned end portions each offset end portion having a pair of integral lugs extending at substantially right angles to said body portion, the lugs of each pair being bent upwardly with 40 respect to said body portion into substantial parallelism with each other, and means on said body portion to provide for attachment thereof to a suitable support the lugs of one of said pairs being adapted to receive an 45 electrode of a vacuum tube and the lugs of the other pair being adapted for permanent attachment thereto of a terminal wire.

6. A combined contact clip and terminal for vacuum tube sockets, comprising a 50 metal blank having a relatively long body portion and opposite end portions each having a pair of integral lugs extending at substantially right angles to said body portion, the lugs at one end being relatively small and 55 being bent upwardly into substantial parallelism with each other to receive a terminal wire, the lugs at the other end being also bent upwardly and having the tips thereof flared apart to facilitate passage of a vacuum 60 tube electrode therebetween, said body portion being bent intermediate its ends to provide offset portions adapted to lie in parallel longitudinal planes, and said body portion 65 being also provided with a screw-threaded

opening to provide for adjustable securing thereof to an insulating base.

7. A socket construction for conductor containing bulbs having contacts, comprising a receptacle shell for the bulb, a base 70 extending across the rear face of said shell, and a plurality of electrically conductive members each extending flatwise of the base from wiring terminals thereon for direct contact engagement with the bulb contacts 75 and each also having clamping engagement with the receptacle to secure the receptacle to the base.

8. In a radio tube socket construction having an insulating receptacle shell and base, 80 a single current conducting member having a wiring terminal portion engaging the base, said member also having a portion for contacting with an electrode of a tube, and said member also having an intermediate 85 portion in clamping engagement with the insulating shell to secure said shell to the base.

In witness whereof, we have hereunto subscribed our names. 90

CERTIFICATE OF CORRECTION.

Patent No. 1,767,690.

Granted June 24, 1930, to

GEORGE J. MEUER ET AL.

It is hereby certified that error appears in the printed specification of the above numbered patent requiring correction as follows: Page 3, line 36, claim 5, strike out the word "offset" and insert same after the word "alined" in line 35; and that the said Letters Patent should be read with this correction therein that the same may conform to the record of the case in the Patent Office.

Signed and sealed this 9th day of September, A. D. 1930.
